UNITED STATES PATENT OFFICE.

OTTO HERMAN ERDMAN, OF BIRMINGHAM, ALABAMA.

FURNACE-GRAVE.

1,105,636.

Specification of Letters Patent.

Patented Aug. 4, 1914.

Application filed February 9, 1914. Serial No. 317,397.

To all whom it may concern:

Be it known that I, OTTO HERMAN ERDMAN, a citizen of the United States, residing in the city of Birmingham and State of Alabama, have invented a new and useful Furnace-Grate, of which the following is a specification.

This invention relates to furnace grates and consists in the novel construction, combination and arrangement of parts herein-after more fully disclosed.

The object of the invention, generally, is to provide an improved grate construction, comprising a plurality of hollow grate bars so constructed as to permit the use of a forced draft or natural draft, as desired, and upon which, fuel of various kinds may be burned to substantially complete combustion. With this object, as well as the attainment of certain other specific improved features of construction in view, which will be apparent to those skilled in the art, I have designed, combined and arranged the several parts herein-after more fully disclosed, reference being made to the accompanying drawing, in which—

Figure 1 is a broken plan view of the grate construction showing a plurality of the grate bars in assembled relation. Fig. 2 is an end view partially in elevation and partially in section showing the arrangement of a furnace grate embodying my invention. Fig. 3 is a longitudinal section through the fire box of a furnace embodying my invention.

In the preferred embodiment of my invention, as illustrated in the drawing, my invention comprises a series of hollow grate bars preferably made in two matching sections 40 and supported side by side to form a fuel supporting bed, with provision for introducing a forced draft into each bar, from which it is forced out through the fuel supporting walls of the bars beneath the bed of fuel.

Each of the grate bars comprises a lower section, preferably of cast iron, formed with inwardly beveled side walls 1, an inwardly inclined front end wall 2, and a rear wall 3, and an upper section.

The bottom section of each bar is provided with an outwardly extending flange 4 extending from the front wall 2, and flanges 5 and a flange 6 extending outwardly, respectively, from the side walls 1 and rear end wall 3. The upper section of each grate bar fits over the upper portion of the lower

section and rests upon the said flanges 4, 5 and 6 in the manner clearly illustrated in the drawings.

The several grate bars are supported longitudinally of the furnace upon a front bearing bar 7, suitably supported by the side walls 8 of the furnace, and a rear bearing member 9 supported by the rear or bridge wall 10 of the furnace. The flanges 4 extend forwardly and rest upon the front bearing bar 7, when the flanges 6 are in position upon the upper portion of the rear bearing member 9. The side walls 1 of each lower section are connected intermediate of their ends by a central bearing block 11 which serves the dual function of a brace for the said side walls and a bearing for the shaker bars, as hereinafter explained. The upper face of the bearing block 11 is beveled to prevent the accumulation thereon of ashes and other residue of combustion which sifts to the inside of the grate bars. The edges of the bearing blocks 11 are formed with extended flanges 12 which fit closely upon the shaker bars 14.

The side walls 1 of the lower section of the grate bars do not meet at the bottom, but there remains in each lower section of the bars, an opening 13 for the removal of the accumulations therein, and also for the admission of natural draft through the ash pit of the furnace. These openings 13 in the bottom of the grate bars are controlled by a series of shaker bars. Each of the shaker bars 14, is formed with a beveled or arcuate face 15, which when the shaker bars are mounted in position below the openings in the lower sections of the grate bars, form a closure for the said openings. For each

grate bar I prefer to provide two shaker bars 14 arranged end to end. Extending from the ends of the shaker bars 14 are trunnions 16; those of the forward shaker bar being mounted in a journal box 17 formed in the front walls 2 of each lower section of the grate bars, and in a journal 18 formed in the blocks 11, and those of the rearward shaker bar being journaled in the journal box 18, and a journal box 19 formed in a block 20 cast integral with the lower section of the grate bar. Each of said journal boxes is provided with the usual cap so that the shaker bars may be readily removed or replaced.

The shaker bars 14 are mounted to rock in unison, for the purpose of removing accumu-

lations of ash, dust and the like for the grate bars, and also for partially opening the bottom of the grate bars for the admission of a natural draft from the ash pit.

5 Each of the shaker bars 14 is provided with a depending arm 21, the transverse series of said arms being connected together for joint oscillation by links 22. Each end of the links 22 is hinged as shown at 23, to an

10 end of an arm of a shaker bar, mounted in each outside grate bar, and the arms of the shaker bars mounted in the intermediate grate bars extend through slots 24 in the links 22. On the lower face of each link 22

15 are arranged spaced angle plates 24^a, disposed substantially intermediate of the length of the links 22. A rod 25 is mounted below said links 22, said rod being journaled in the fire front 26 of the furnace and in the

20 rear or bridge wall 10 of the furnace. A lever 27 secured to the end of the rod 25 which extends through the fire front 26 provides means for manually rocking said rod

25. Collars 28 are adapted to be set on said

25 rod 25, said collars having extending arms 29, arranged to engage the angle plates 24^a depending from the links 22, when the rod 25 is rocked, thereby imparting to the shaker bars 14 oscillating motion alternately

30 opening a space in the bottom of the grate bars at the edge of each side wall. It will be noted, that inasmuch as all surfaces of the parts within the lower part of each grate bar incline to the upper face of the

35 shaker bars, by rocking the shaker bars in the manner described all accumulations can be removed from the bars. Access to the ash pit for removal of the accumulations deposited therein may, as will be understood,

40 be had through the usual ash door opening 30.

At the rear of the furnace is formed an air conduit 31, for which the rear bearing member 9 forms a top. At intervals, corresponding to the spacing of the grate bars, there is formed in said member 9, which is an integral iron casting, upwardly extending passages or air conduits 32 over the upper edges of which the walls of an opening 33 in the bottom of the respective grate bars are adapted to engage. I prefer to seal or pack the joint between the passage 32 and 33 by placing packing 34 in grooves 35 formed in the matching edges of the conduits. A forced current of air may be introduced into conduit 32 and thence via the passages 33 to the interior of the grate bars, from any suitable source.

The upper section of each of the grate bars comprises side walls 36, a front wall 37, a rear wall 38, and a top or fuel supporting wall 39. The front wall 37 extends above the rear wall 38 and above the horizontal level of the fuel supporting wall 39, thus

65 providing an upwardly inclined surface at

the forward end of the bar. This construction facilitates the removal of accumulations on the face of the grate bars, and provides for ejecting a part of the forced draft at an acute angle to the bed of fuel, thus promoting the combustion thereof.

The top or fuel supporting walls 39 of the grate bars are arched upwardly and are provided with a series of transverse slots or slits 40 through which the forced draft 75 is ejected against the lower surface of the bed of fuel supported by the furnace bed, in such a manner that the jets of air will be forced upwardly and obliquely, the jets from the laterally adjacent slit intersecting each other, thus delivering a forced draft to all parts of the bed of fuel. These slits can be made as narrow as desired so that fuel in a finely divided state can be supported by the furnace bed without passing therethrough. 85 Transverse ribs 41 are provided on the inner surface of the top wall to strengthen the web between the slits 40.

The upper and lower sections of the grate bars fit securely together, and are mounted 90 side by side as has been explained. The adjacent edges of the side flanges 5 are spaced slightly apart and the upper edge of each flange is formed with rounded grooves 42. This slight spacing of the bars is required to provide for expansion of the bars under the influence of heat, but in order to prevent a draft from the ash pit entering the fire box of the furnace, I mount hollow pipe 43 in the grooves 42 thereby providing a 100 seal for the openings or spaces between the bars, which will be adjustable to accommodate itself to the expansion and contraction of the flanges.

I am aware that numerous changes in the 105 construction and arrangement of the parts hereinbefore described may be made without departing from the spirit and scope of my invention. I do not limit myself, therefore, to exact details but.

What I claim and desire to secure by Letters Patent is:

1. A furnace grate comprising a series of hollow grate bars arranged with air delivering slits in the upper portions thereof and an ash removing opening in the bottom of the same, each of said bars being provided with outwardly extending flanges from the front and rear wall adapted to engage over a front and rear bearing bar for supporting 115 said bars in transverse arrangement, longitudinal flanges extending from the sides of said bars, said flanges being provided with grooves in their upper edge, and a series of rounded bars adapted to rest in said grooves and constitute an adjustable seal for preventing the admission of air from the ash pit to the fire box of the furnace, substantially as specified.

2. A furnace grate, comprising a series of 130

transverse supporting beams, a series of hollow grate bars supported side by side on said beams, an air supply conduit running transversely across the back of the furnace 5 below said beams, a passage in each of said bars adapted to receive the air from said air supply conduit, means for sealing the joint between said air supply conduit and said passage opening into said bars, a series of 10 slits through the top walls of said bars for delivering a forced draft to the bed of fuel supported thereon, a longitudinal opening through each of the bottom walls of said bars, a series of shaker bars pivotally supported below said openings in the bottom of said bars, the pivots being below the center of said openings, connections between said shaker bars whereby said bars may be operated in unison to open or close said openings, 15 and means for adjustably sealing the spaces between the adjacent edges of said grate bars, substantially as specified.

3. In a furnace, the combination of a series of hollow grate bars having openings 20 through their lower sides and laterally extending flanges adjacently disposed across the furnace, rounded rods adjustably closing the spaces between said flanges, a series of shaker bars controlling the openings in the 25 lower sides of said bars, and manually operable connections for jointly operating said shaker bars.

4. A grate, comprising a series of hollow bars, means for supporting said bars side 30 by side, each of said bars comprising an upper and a lower section, the upper section being provided with a fuel supporting wall having a series of transverse slits, a series of depending reinforcing webs on the inner 35 face of said wall and having an upwardly inclined portion at one end thereof, the lower section of each of said bars having converging side walls and an open bottom, bearings formed integral with said lower

section at each end thereof, and a bearing 45 in said lower section substantially intermediate of its length, a series of rockable bars pivoted at one end in the bearings formed at the front end of each of said lower sections and at the other end in said intermediate bearings, a second series of rockable bars pivoted in said intermediate bearings and in the bearing formed at the rear end of each bar, said rockable bars being provided with an arcuate face adapted to form 50 a closure between the side walls of each lower section, connections between the front series of rockable bars, connections between the rear series of rockable bars, and manipulative means whereby all of said bars may 55 be rocked in unison in either direction, substantially as specified.

5. A hollow grate bar adapted for use in a forced draft furnace grate, comprising an upper and a lower section, said upper section having an arched fuel supporting wall provided with a series of transverse slits, a series of depending webs formed integral with the inner face of said fuel supporting wall and disposed intermediate of said slits, the forward end of said fuel supporting wall extending obliquely upwardly and having therein a series of transverse slits adapted to deliver transverse jets of air at 65 an acute angle to the jets of air delivered by the slits formed in the main body of the fuel supporting wall, and a passage entering the lower section of said grate bar for delivering a forced draft to the interior of the bar, substantially as specified. 70

In witness whereof, I have signed this specification in the presence of two subscribing witnesses.

OTTO HERMAN ERDMAN.
